HAND-LEVEL CONSTRUCTION.

1,111,677.

Specification of Letters Patent. Patented Sept. 22, 1914.

Application filed March 12, 1914. Serial No. 824,109.

To all whom it may concern:

Be it known that I, EDMUND A. SCHADE, a citizen of the United States, residing at New Britain, county of Hartford, State of Connecticut, have invented certain new and useful Improvements in Hand-Level Construction, of which the following is a full, clear, and exact description.

This invention relates to improvements 10 in hand levels and more specifically to improved means whereby the level may be readily held in adjusted position by one hand of the operator, while with the other hand, a suitable marking tool is drawn 15 along the straight edge of the level.

The present invention relates to that type 20 of holding means involving a plurality of pointed holding members carried by the level body and arranged to penetrate into the wood and assist in maintaining the level body in adjusted position. With such 25 a hand level provided with these holding pins, it has been found that these pins frequently inflict deep scratches and wounds in the hands and tear clothing unless the operator is very careful. Furthermore, in 30 the type of holding pin heretofore used, it has been possible to lose a holding pin inasmuch as no retaining means for the pin 35 has been provided. I overcome these two faults in the present invention which is described in detail in the following specification, and of which a preferable embodiment is illustrated in the accompanying drawings forming part thereof and in which

Figure 1 is a view in rear elevation of a standard form of hand level equipped with the devices of the present invention. Fig. 40 2 is a vertical section through said level on the line of one of said devices, the holding pin being projected for supporting engagement. Fig. 3 is a similar view but with the pin retracted to inoperative position.

In these drawings 1 designates generally 45 the body of a metal hand level having the usual parallel longitudinal straight edges 2 and the end straight edges 3. This level body may be of any standard type such as that shown in the drawings and is provided with level glasses 4 extending transversely thereof and facing in opposite directions, a third level glass 5 being also preferably

provided, this last glass extending longitudinally of the level body, so that accuracy of alinement can be obtained.

My improvement consists in applying to a level body, such as one of this type, the pointed holding means preferably constructed as follows. At two or more points longitudinally of the level body, the latter is provided with transverse threaded bores therein. Screwing into these bores is an externally and internally threaded sleeve 6 having one end open and provided with an annular flange 7, and having its other end provided with a similar flange and with an aperture therethrough. This is preferably accomplished by utilizing a short externally and internally threaded sleeve section 8 having an annular end flange 9. The external diameter of the section 8 is equal substantially to the internal diameter of the main sleeve body 6. The main body 75 of the sleeve member is screwed through the level bore first, and the sleeve section 8 is then screwed into the open end of the sleeve 6 from the opposite side of the body, this being the easiest method of assembling. Subsequent to this, these two parts may be 80 rigidly interconnected against movement in any suitable manner, so that thereafter they may not be separated. In ordinary practice the construction shown in the drawings 85 may be employed inasmuch as the thread interlock between the main body 6 and the short section 8 of the sleeve structure may be made sufficiently firm to prevent relative movement thereafter. It will be evident 90 that the flanges 7 and 9 will prevent the sleeve from being removed from the level body after once having been attached.

From the flange end 7 of the sleeve body, a pointed pin 10 is screwed into and through the threaded interior bore of the sleeve section 8 until the pointed end of the pin projects beyond the face of the flanged end 9 of said sleeve section. The rear end of this pin is provided with a head 11 limiting the amount of projection of its pointed end, this head preferably having a screw driver slot therein so that a screw driver may have its end inserted through the open flanged end 7 of the sleeve structure to engage with the slot in the head of this pin, and to either retract the pointed end of the pin wholly within the sleeve structure or

project the same therefrom as may be desired.

The overall length of the sleeve member including the flanged ends 7-9 and projected pin 10, is preferably less than the greatest overall thickness of the level body, so that when the rear end of the sleeve member is screwed up, the said sleeve may be positioned to have its flanges 7-9 within the plane of the extreme outer faces of the level body and, therefore, in a position where they will not interfere with the ordinary handling of the tool. The sleeve is also, preferably, of such length that when it is screwed up to bring the outer end 7 against the adjacent face of the level body, the inner end 9 will be positioned approximately in the plane of the opposite inner face of the level body. With the holding pin 10 projected from this outer face 9, it will be evident that in this position of the level body, the pins may be forced into the wood, for instance, against which the level body rests, and will enable the workman to hold the adjusted level with one hand while with the other he scribes or otherwise marks the desired line upon the wood. It will also be evident that when the level is not being used for such work, the points of the pin 10 may be withdrawn within the sleeve member by inserting the end of a screw driver through the open end 7 of the sleeve and screwing the pin 10 inside of the opposite end of said sleeve. Furthermore, inasmuch as the parts of a sleeve body are fixed against relative movement under ordinary circumstances, the pin-carrying sleeve member cannot be lost from the level body. Furthermore, the sleeve member is of such length relative to the overall thickness of the level body, that it may be positioned relative thereto so as not to interfere with ordinary work when the holding device is not needed. I have herein described and shown a specific embodiment of my invention, but it will be evident that the invention is susceptible of modification both in structure and in the relative arrangement of parts within the spirit of the invention and the scope of the appended claims.

What I claim, therefore, and desire to secure by Letters Patent is:

1. Supporting means for hand levels comprising in combination with the level body, a plurality of members carried by and extending transversely through the level body, the greatest overall length of said members not exceeding the greatest overall thickness of the level body, said members having bores extending therethrough, pointed pins extending through said bores and adjustable longitudinally thereof, said pins being projectable from the same side of the level body with means for limiting the amount of projection of the pointed ends of

said pins, said members being arranged to be projected and held with their pointed pins projecting beyond one of their extremities and beyond the plane of the adjacent side bearing surface of the level body for supporting engagement, and being arranged to be retired from such position and held with both ends within the planes of the opposite side bearing surfaces of said level body and with the pointed ends of said pins wholly within their respective bores.

2. Supporting means for hand levels comprising in combination with the level body, a plurality of members carried by and extending transversely through the level body, the greatest overall length of said members not exceeding the greatest overall thickness of the level body, said members having bores extending partially therethrough from one end, the opposite ends of said members being provided with bores of reduced diameter therethrough, pointed pins extending through said last named bores and adjustable longitudinally thereof, said pins being projectable from the same side of the level body with means for limiting the amount of projection of the pointed ends of said pins, said members being arranged to be projected and held with their pointed pins projecting beyond one of their extremities and beyond the plane of the adjacent side bearing surface of the level body for supporting engagement, and being arranged to be retired from such position and held with both ends within the planes of the opposite side bearing surfaces of said level body and with the pointed ends of said pins wholly within their respective bores.

3. Supporting means for hand levels comprising in combination with the level body, a plurality of members carried by and extending transversely through the level body, the greatest overall length of said members not exceeding the greatest overall thickness of the level body, said members having bores extending partially therethrough from one end, the opposite ends of said members being provided with threaded bores of reduced diameter extending therethrough, threaded pins cooperating with and movable longitudinally of said bores and having pointed ends arranged to be projected a limited distance beyond the ends of said members, said pins having their opposite ends formed for manual control, said members being arranged to be projected and held with the pointed ends of said pins in projected position and extending slightly beyond the plane of the adjacent side bearing surface of the level body for supporting engagement, said members being also arranged to be retired from such position and held with both ends within the planes of the opposite side bearing surfaces of said level body, the

pointed ends of said pins being manually retractable wholly within the bores of said members.

4. Supporting means for hand levels comprising in combination with the level body, a plurality of threaded members extending through transverse threaded bores in the level body, said members having bores extending partially therethrough from their 5 same relative ends, the opposite ends of said members being provided with bores of reduced diameter, threaded pins for operating in the said threaded bores and having pointed ends arranged to project a limited distance 10 from said members and from the same side of the level body, the opposite ends of said pins being formed for manual control,

and the greatest overall length of said members not exceeding the greatest overall thickness of the level body, said members having 20 stop abutments adjacent their ends to retain them on said body and in said level bores and being of such length that they may be projected to bring the pointed ends of said pins beyond the plane of the adjacent side 25 bearing surface of the level body for supporting engagement, the pointed ends of said pins being manually retractable wholly within their respective bores.
